Thomas Chambers.

THOMAS CHAMBERS, OF ST. LOUIS, MISSOURI.

Letters Patent No. 83,691, dated November 3, 1868.

IMPROVEMENT IN PUMPS.

The Schedule referred to in these Letters Patent and making part of the same.

To all whom it may concern:

Be it known that I, THOMAS CHAMBERS, of the city and county of St. Louis, and State of Missouri, have invented a new and useful Improvement in Force-Pumps; and I do hereby declare that the following is a full and clear description thereof, reference being had to the accompanying drawings, and to the letters of reference marked thereon.

The nature of this invention consists in the employment of a small cylinder and piston, in connection with a larger one, the power being applied to the smaller piston, which is used to force water or other fluid against the larger piston, or rather against a small auxiliary piston connected therewith; the object being to cause the large piston to force a large amount of water, or other fluid, from its cylinder, by means of a comparatively small force applied to the smaller piston, and a correspondingly small motion of the latter piston.

To enable those skilled in the art to make and use my improved pump, I will proceed to describe its construction and operation.

Figure 1 of the drawings is a sectional elevation of one of the improved pumps.

Figure 2 is a sectional elevation of one of the valves.

Figure 3 shows a variation in the form of the valve that may be employed.

A and B are the two large cylinders, which are to be joined together by their ends *a b*, so as to allow the two pistons *A' B'* to work back and forth in their respective cylinders, and have a common piston-rod, C.

The auxiliary cylinder D, connected with the outer end of the cylinder A, and the cylinder E, connected with the outer end of the cylinder B, are much smaller in diameter, (say one-half,) than the cylinders A B, and they have correspondingly-diminished pistons *D' E'*, secured to prolongations of the rod C, which said prolongations of said rod pass through stuffing-boxes in the heads *d e*.

Connected with the outer ends of the cylinders D E, by means of sleeves *F F'*, are forcing-cylinders *F'' F'*, which have pistons *F'' F'*, worked by rods *F'' F'*.

The spaces between the pistons *D' E'* and the heads *d e*, also those between the pistons *A' B'* and the heads *a b*, are intended to be air or vacuum-chambers, as may be found most expedient.

Valve-openings *d' e'*, either with or without valves, may be supplied to either or all of these chambers, as may be desired; also waste-cocks or pipes *d'' e''*, for the purpose of drawing off any condensed moisture that may accumulate therein, or water that may leak through the packing of the piston or cylinder-head.

The induction-pipes *G* supply water, or other fluid, to the cylinders A B, and the eduction-pipes *G'* conduct the said fluid therefrom to the place to which it is to be forced or elevated. The valves *g*, used in these pipes, are of new and peculiar construction.

The valve-chambers *g'* are hollow spheres, the lower portions of which form the valve-seats. The valves *g* are arranged to fit the concave seats thus formed, and consequently the valve will rest firmly on its seat, no matter if it be turned a little to one side or the other.

These valves may have a single central stem, *g²*, to each, the said stem being guided by the cross-rods *g³*, or each valve may have wings *g⁴* for guides, as is shown in fig. 3.

The pump constructed as above described, the operation will be as follows:

The sleeves *F F'*, between the pistons *F'' F'* and *D' E'*, are supposed to be filled with water, or some other fluid, and one of the pistons *F''* up, and the other down. These two latter pistons should be connected with the opposite ends of the same lever, not shown, so that their upward and downward motions may harmonize with each other in a reciprocating manner. When one of the pistons *F''* is forced down, it will press the fluid between it and the piston adjacent to it, up against the said piston, so as to force it back to the other end of its cylinder through the vacuum or air-space contained therein. This motion will necessitate a corresponding motion of the pistons *A' B'*, and consequently their increased area will force a correspondingly large quantity of fluid up through the pipes *G'* at each stroke of the pistons. Thus, by the expenditure of a limited amount of power to the pistons *F''*, and that power applied in a slow time, a very large amount of fluid may be forced upward from the cylinder A or B.

Although, from the foregoing description, it appears that two of the cylinders A B are, or may be, used together, thus forming what is usually denominated a double-acting pump, it is apparent that one-half of the machine thus described may be left off if desirable, and then leave a perfect-working, single-acting pump. If this division of the machine should be made, it will be found necessary to introduce some spring, or something of the kind into the vacuum-end of the large cylinder used, so as to force the large piston back when it is unloaded.

The principal object for which this pump was designed, was to throw a large quantity of water to the top of a building, by a small appliance of power, but longer continued, the said water, so elevated, to be used to raise weights in a dumb-waiter or elevator.

Having described my invention,

What I claim is—

A large forcing-cylinder, A or B, a vacuum or air-cylinder, D or E, and a small forcing-cylinder, F', when combined substantially in the manner and for the purpose set forth.

THOMAS CHAMBERS.
